COMPOSITION USEFUL AS AN ANTIOXIDANT
FOR FATS AND OILSJames E. Magoffin, Kingsport, Tenn., assignor to
Eastman Kodak Company, Rochester, N. Y., a
corporation of New JerseyNo Drawing. Application July 26, 1949,
Serial No. 106,957

8 Claims. (Cl. 252—404)

1

This invention relates to a composition useful as an antioxidant for fats and oils. This application is a continuation-in-part of my application Serial No. 81,842, filed March 16, 1949, now abandoned.

It has long been known that phenols, such as hydroquinone, guaiacol, eugenol, gallic acid and its esters, e. g. tannin (penta-1m-digalloylglucose), etc. are useful as antioxidants for fats and oils (Moureau et al. Compt. rend. 174, 258 (1922)). It is also known that the phenolic compounds such as the alkylated hydroxyphenyl ethers (for example, alkylated hydroxyanisoles, etc.) can be used as antioxidants for fats and oils. It is further known that the antioxidant action of such phenolic antioxidants can be synergized with acids, e. g. citric acid, orthophosphoric acid, tartaric acid, etc. While these phenolic compounds, as well as their synergistic combinations with acids, such as citric acid, etc. have been found to be adequately effective in retarding oxidative rancidity during storage of fats and oils, they are subject to the disability in many instances of being only slightly soluble in the fatty materials to which they are added. In processing such fats and oils, a considerable percentage of the effective amounts of the antioxidants are frequently lost due to this lack of sufficient solubility.

I have now found that the dispersion of mixtures of certain of these antioxidants in fats and oils can be materially improved if a concentrate of these antioxidants in propylene glycol is employed. This concentrate has the advantage of materially increasing the solubility or dispersability of mixtures of certain of the antioxidants in the fatty material to be stabilized, thus enabling one to secure uniformly dispersed mixtures of the antioxidant in the fatty materials and more effectively to prevent oxidation with a given proportion of antioxidant to fat.

According to my invention, one or more gallic esters with one or more alkylated hydroxyphenyl ethers, with or without one or more synergizing acids, can be dispersed in propylene glycol to give a concentrate which is highly useful as an antioxidant for fats and oils.

Advantageously, the total weight of the gallic ester in the concentrate is from 3 to 30 per cent of the total weight of the concentrate, the remainder being propylene glycol plus at least one alkylated hydroxyphenyl ether, or propylene glycol plus at least one alkylated hydroxyphenyl ether plus at least one synergizing acid.

The total weight of the alkylated hydroxyphenyl ether is advantageously from 10 to 50 per cent of the total weight of the concentrate. Where at least one synergizing acid is employed, the total weight of the synergizing acid is advantageously from 3 to 10 per cent of the total weight of the concentrate. In no case should the weight

2

of propylene glycol be less than from 20 to 80 per cent of the total weight of the concentrate.

Advantageously the total weight of the alkylated hydroxyphenyl ether employed is from 1.0 to 5 times the total weight of the gallic ester. Advantageously the total weight of the synergizing acid is from 0.2 to 1 times the total weight of the gallic ester.

The gallic esters which I employ in practicing my invention can be represented by the following general formula:

wherein R represents an alkyl group containing from 1 to 5 carbon atoms, e. g. methyl, ethyl, n-propyl, isopropyl, n-butyl, isobutyl, n-amyl, etc. Typical examples are: methyl gallate, ethyl gallate, n-propyl gallate, isopropyl gallate, n-butyl gallate, isobutyl gallate, n-amyl gallate, etc.

The alkylated hydroxyphenyl ethers which I employ in practicing my invention can be represented by the following general formula:

wherein R₁ represents an alkyl group containing from 1 to 2 carbon atoms, and R₂ represents a tertiary alkyl group containing from 4 to 5 carbon atoms. Typical examples are: 2-tert. butyl-4-hydroxyanisole, 3-tert. butyl-4-hydroxyanisole, 2 - tert. butyl-4-hydroxyphenetole, 3-tert. butyl - 4 - hydroxyphenetole, 3-tert. amyl-4-hydroxyanisole, 3-tert. amyl-4-hydroxyphenetole, etc.

Among the synergizing acids which I employ are: citric acid, orthophosphoric acid, tartaric acid, ascorbic acid, etc.

Efficacious concentrates are set forth in the following examples:

Example 1		Parts by weight
Propylene glycol		60
Butylated hydroxyanisole		23.5
n-Propyl gallate		11.8
Citric acid		4.7

The above concentrate is of such composition that one pound is sufficient to stabilize one ton of lard. Such a concentrate is a homogeneous system even at temperatures as low as -20° C.

3

It is, therefore, capable of being manufactured and handled in ordinary channels of commerce without separation of the added components. Propylene glycol is satisfactory for incorporation in edible products in concentrations much greater than result from use of this mixture. In contrast to propylene glycol, a material such as glycerin will not function in a satisfactory manner.

In contrast to fats stabilized against oxidative rancidity with mixtures of the aforesaid antioxidants without the use of propylene glycol as a dispersing medium, fats stabilized with the concentrate set forth in the above example contained the antioxidant dispersed throughout the entire body of the fat, thus enabling the fatty material to be stored for longer periods of time, and also to be further processed (as, for example, by cooking, etc.) without serious depletion of the antioxidant, to give products which are also stable to the influences of oxidative rancidity.

In the above example, the n-propyl gallate can be replaced with an equal weight of methyl gallate (gallicin), ethyl gallate, isopropyl gallate, n-butyl gallate, n-amyl gallate, etc. Likewise, the citric acid can be replaced with an equal weight of ascorbic acid, orthophosphoric acid or tartaric acid. 25

The "butylated hydroxyanisole" of the above example is a mixture of equal parts by weight of: 30

3-*tert*-butyl-4-hydroxyanisole

end

2-tert-butyl-4-hydroxyanisole

Instead of this mixture an equal weight of either 3-tert. butyl-4-hydroxyanisole or 2-tert. butyl-4-hydroxyanisole can be employed, or an equal weight of 2-tert. butyl-4-hydroxyphenetole, 3-tert. butyl-4-hydroxyphenetole, 2-tert. amyl-4-hydroxyanisole, 3-tert. amyl-4-hydroxyanisole, 2-tert. amyl-4-hydroxyphenetole or 3-tert. amyl-4-hydroxyphenetole can be employed.

Example 2

Parts by weight

Propylene glycol	30
Butylated hydroxyanisole	41.2
n-Propyl gallate	20.6
Citric acid	8.2

Such a concentrate is a homogeneous system even at temperatures as low as -20°C . As in Example 1, the n-propyl gallate can be replaced with methyl gallate (gallicin), ethyl gallate, isopropyl gallate, n-butyl gallate or n-amyl gallate. The citric acid can be replaced with ascorbic acid, orthophosphoric acid or tartaric acid. The "butylated hydroxyanisole" has the same meaning as in Example 1 and can be replaced with 3-tert. butyl-4-hydroxyanisole or 2-tert. butyl-4-hydroxyanisole or by 2-tert. butyl-4-hydroxyphenetole, 3-tert. butyl-4-hydroxyphenetole, 2-

4

tert. amyl-4-hydroxyanisole, 3-tert. amyl-4-hydroxyanisole, 2-tert. amyl-4-hydroxyphenetole or 3-tert. amyl-4-hydroxyphenetole.

Example 3

Parts by weight

Such a concentrate is a homogeneous system even at temperatures as low as -20° C . As in Example 1, the n-propyl gallate can be replaced with methyl gallate (gallicin), ethyl gallate, isopropyl gallate, n-butyl gallate or n-amyl gallate. The citric acid can be replaced with ascorbic acid, orthophosphoric acid, metaphosphoric acid, tartaric acid, etc. The "butylated hydroxyanisole" has the same meaning as in Example 1, and can be replaced with 3-tert. butyl-4-hydroxyanisole or 2-tert. butyl-4-hydroxyanisole or by 2-tert. butyl-4-hydroxyphenetole, 3-tert. butyl-4-hydroxyphenetole, 2-tert. amyl-4-hydroxyanisole, 3-tert. amyl-4-hydroxyanisole, 2-tert. amyl-4-hydroxyphenetole or 3-tert. amyl-4-hydroxyphenetole.

My concentrate can be employed to stabilize all fats and oils, e. g. glycerides of fatty acids, such as lard, tallow, peanut oil, palm oil, cocoanut oil, cottonseed oil, soya bean oil, sunflower-seed oil, sesame oil, hydrogenated oils or shortenings (especially those of the dry plastic type) and fat and oil mixtures.

By the term "propylene glycol," I mean the compound which has the following formula:

The alkylated hydroxyphenyl ethers can be prepared by reacting p-hydroxyanisole or p-hydroxyphenetole with tert. butyl or tert. amy1 alcohol, at a temperature of from 80° to 90° C. in the presence of phosphoric acid as a catalyst. The alkylated hydroxyphenyl ethers can also be prepared by reacting p-hydroxyanisole or p-hydroxyphenetole with isobutylene or with isoamylene, in the presence of sulfuric acid.

The gallic esters which I employ in practicing my invention can be prepared as described by Hepner and Zito, Roczniki Chemii 12, 100 (1932).

1 50. What I claim as my invention and desire to
be secured by Letters Patent of the United States
is:

1. A concentrate containing propylene glycol at least one gallic ester selected from the group 55 consisting of those represented by the following general formula:

wherein R represents an alkyl group containing from 1 to 5 carbon atoms, and at least one alkylated hydroxyphenyl ether selected from those represented by the following general formula:

5

wherein R₁ represents an alkyl group containing from 1 to 2 carbon atoms, and R₂ represents a tertiary alkyl group containing from 4 to 5 carbon atoms, the total weight of gallic ester being from 3 to 30 percent of the total weight of the concentrate, and the total weight of the alkylated hydroxyphenyl ether being from 10 to 50 percent of the total weight of the concentrate.

2. A concentrate containing propylene glycol, at least one gallic ester selected from the group consisting of those represented by the following general formula:

wherein R represents an alkyl group containing from 1 to 5 carbon atoms, at least one alkylated hydroxyphenyl ether selected from the group represented by the following general formula:

wherein R₁ represents an alkyl group containing from 1 to 2 carbon atoms and R₂ represents a tertiary alkyl group containing from 4 to 5 carbon atoms, and at least one synergizing acid selected from the group consisting of citric acid, orthophosphoric acid, tartaric acid and ascorbic acid, the total weight of the gallic ester being from 3 to 30 percent by weight of the total weight of the concentrate, the total weight of the alkylated hydroxyphenyl ether being from 10 to 50 percent of the total weight of the concentrate, and the total weight of the synergizing acid being from 3 to 10 percent of the total weight of the concentrate, the weight of the propylene glycol being from 20 to 80 percent of the total weight of the concentrate.

3. A concentrate containing propylene glycol, at least one gallic ester selected from the group consisting of those represented by the following general formula:

wherein R represents an alkyl group containing from 1 to 5 carbon atoms, at least one alkylated hydroxyphenyl ether selected from the group represented by the following general formula:

wherein R₁ represents an alkyl group containing from 1 to 2 carbon atoms and R₂ represents a tertiary alkyl group containing from 4 to 5 carbon atoms, and at least one synergizing acid selected from the group consisting of citric acid, orthophosphoric acid, tartaric acid and ascorbic

6

acid, the total weight of the gallic ester being from 3 to 30 percent by weight of the total weight of the concentrate, the total weight of the alkylated hydroxyphenyl ether being from 10 to 50 percent of the total weight of the concentrate, and the total weight of the synergizing acid being from 3 to 10 percent of the total weight of the concentrate, the weight of the propylene glycol being from 20 to 80 percent of the total weight of the concentrate, the total weight of the alkylated hydroxyphenyl ether being from 1.0 to 5 times the total weight of the gallic ester and the total weight of the synergizing acid being from 0.2 to 1 times the total weight of the gallic ester.

15 4. A concentrate containing propylene glycol, n-propyl gallate, a mixture of 2-tert. butyl-4-hydroxyanisole and 3-tert. butyl-4-hydroxyanisole and citric acid, the weight of the n-propyl gallate being from 3 to 30 percent of the total weight of the concentrate, the weight of the mixture of 2-tert. butyl-4-hydroxyanisole and 3-tert. butyl-4-hydroxyanisole being from 10 to 50 percent of the total weight of the concentrate, the weight of the citric acid being from 3 to 10 percent of the total weight of the concentrate, the weight of the propylene glycol being from 20 to 80 percent of the total weight of the concentrate.

30 5. A concentrate containing propylene glycol, n-propyl gallate, a mixture of 2-tert. butyl-4-hydroxyanisole and 3-tert. butyl-4-hydroxyanisole and citric acid, the weight of the n-propyl gallate being from 3 to 30 percent of the total weight of the concentrate, the weight of the mixture of 2-tert. butyl-4-hydroxyanisole and 3-tert. butyl-4-hydroxyanisole being from 10 to 50 percent of the total weight of the concentrate, the weight of the citric acid being from 3 to 10 percent of the total weight of the concentrate, the weight of the propylene glycol being from 20 to 40 80 percent of the total weight of the concentrate, the total weight of the mixture of the 2-tert. butyl-4-hydroxyanisole and 3-tert. butyl-4-hydroxyanisole being from 1.0 to 5 times the weight of the n-propyl gallate and the weight of the citric acid being from 0.2 to 1 times the weight of the n-propyl gallate and the weight of the citric acid being from 0.2 to 1 times the weight of the n-propyl gallate.

6. A concentrate having the following composition:

		Parts by weight
	Propylene glycol	60
	Mixture of 2-tert. butyl-4-hydroxyanisole	
	and 3-tert. butyl-4-hydroxyanisole	23.5
55	n-Propyl gallate	11.8
	Citric acid	4.7

7. A concentrate having the following composition:

Parts by weight	
60 Propylene glycol	30
Mixture of 2-tert. butyl-4-hydroxyanisole	
and 3-tert. butyl-4-hydroxyanisole	41.2
n-Propyl gallate	20.6
Citric acid	8.2

65 8. A concentrate having the following composition:

		Parts by weight
	Propylene glycol	70
70	Mixture of 2-tert. butyl-4-hydroxyanisole and 3-tert. butyl-4-hydroxyanisole	20
	n-Propyl gallate	6
	Citric acide	4
